(57) CLAIM

The ornamental design for a wine rack, as shown and described.

DESCRIPTION

FIG. 1 is a front elevation view of a wine rack showing my new design;

FIG. 2 is a back elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a front, top, left-side view perspective view thereof; and,

FIG. 8 is a back, bottom, right-side perspective view being thereof.

The broken lines in the drawings depict portions of the wine rack that form no part of the claimed design.
